DESIGN FOR A TEXTILE FABRIC OR SIMILAR ARTICLE

William Willheim, New York, N. Y., assignor to J. Oltarsh, New York, N. Y.

Application December 5, 1933. Serial No. 49,953

Term of patent 3½ years

To all whom it may concern:

Be it known that I, WILLIAM WILLHEIM, a citizen of the United States, residing at 115 Central Park West, New York, New York, have invented a new, original, and ornamental Design for a Textile Fabric or Similar Article, of which the following is a specification, reference being had to the accompanying drawing, forming a part thereof.

The figure is a plan view of a textile fabric showing one-fourth of my new design. The other three fourths, bearing the same design, are arranged as indicated by the portions beyond the dot and dash lines so as to complete the pattern.

I claim:

The ornamental design for a textile fabric or similar article as shown and described.

In testimony whereof I have signed this specification.

WILLIAM WILLHEIM.
